UNITED STATES PATENT OFFICE

173,167

HAIR BAND OR THE LIKE

Einar Neerup, Oak Park, Ill.

Application January 18, 1954, Serial No. 28,546

Term of patent 14 years

(Cl. D86—10)

To all whom it may concern:

Be it known that I, Einar Neerup, a citizen of the United States, and a resident of Oak Park, in the county of Cook and State of Illinois, have invented a new, original, and ornamental Design for a Hair Band or the like, of which the following is a specification, reference being had to the accompanying drawing, forming part hereof.

In the drawing:

Fig. 1 is a top plan view of a hair band showing my new design;

Fig. 2 is a bottom plan view; and

Fig. 3 is an edge elevational view thereof.

I claim:

The ornamental design for a hair band or the like, substantially as shown.
